N-ALKYL-C-METHYL-BARBITURIC
ACID COMPOUNDS

No Drawing. Application March 17, 1934, Serial
No. 716,223. In Germany March 25, 1933

5 Claims. (Cl. 260—257)

The present invention relates to new barbituric acid derivatives and to a process of preparing the same.

It is known that alkylation of the nitrogen atoms of barbituric acids which are twice substituted at the 5-carbon atom has various effects as to the therapeutic properties of such barbituric acid derivatives, substantially depending on the particular substituents which are present at the 5-carbon atom of the barbituric acid. For instance, by the N-methylation or the N-ethylation of C-aryl-C-alkyl barbituric acids therapeutically active compounds have been obtained which display a prolonged activity as compared with the corresponding non-N-alkylated products. Otherwise the N-alkylated C-cyclopentenyl-and C-cyclohexenyl-C-alkyl-barbituric acids display an action which relatively quickly sets in and relatively quickly ceases, which properties render the said barbituric acid suitable for specific therapeutic purposes. Contrary thereto it is known that certain N-alkylated C,C-dialkyl-barbituric acids are very toxic and cannot be used therapeutically in view of their undesired secondary effects.

In accordance with the present invention new N-alkylated C,C-dialkyl-barbituric acid compounds which are free from the said disadvantages of the known N-alkyl-C,C-dialkyl-barbituric acids are obtainable by the manufacture of such N-alkylated C,C-dialkyl-barbituric acids which contain attached to the 5-carbon atom of the barbituric acid as alkyl groups one methyl group and another alkyl group of at least 3 carbon atoms. The latter alkyl group may be saturated or unsaturated and may be substituted by alicyclic radicals as, for instance, in the cyclohexylethyl radical, or may be present in the form of saturated cyclic alkyl groups. Accordingly the new barbituric acids which, in accordance with the present invention, represent a new group of therapeutically valuable barbituric acids may be defined by the following formula:

In this formula R1 stands for an alkyl, alkenyl, cycloalkyl or cycloalkyl substituted alkyl group which groups contain at least 3 carbon atoms, and X stands for hydrogen or an alkyl group or for a metal, such as sodium, potassium, lithium or calcium.

55 The new compounds display properties which,

in general, render them suitable particularly for the short narcosis without showing any secondary effects.

In accordance with the present invention the new N-mono- or dialkylated C-methyl-C-alkyl-barbituric acids are obtainable by reacting upon a methyl-alkyl-malonic or cyano acetic acid or derivatives thereof, for instance, the esters, amides, amide-acid esters, chlorides, nitriles with an N-mono- or N-dialkylated urea to yield the above characterized N-mono- or N-dialkylated C-methyl-C-alkyl-barbituric acids. The alkyl group substituting the malonic or cyano acetic acid compounds above referred to is an alkyl, alkenyl, cycloalkyl or cycloalkyl substituted alkyl group of at least 3 carbon atoms. The reaction is carried out in the presence of a condensing agent, preferably in the presence of alkali metal alcoholates, such as sodium ethylate, and in the presence of a diluent, particularly in the presence of an alcohol, such as methanol and ethanol. Instead of the alkylated ureas themselves derivatives of N-alkylated ureas may be employed, for instance, N-alkylated guanidines, thioureas and isoureaethers. In such cases the primarily obtained intermediate products, for instance, imino and thiobarbituric acid compounds are subsequently to be transformed into the real barbituric acid in the manner known per se.

The N-mono- or dialkylated barbituric acids being substituted at the 5-carbon atom by a methyl group and an alkyl group of at least 3 carbon atoms as specified above are also obtainable by starting with the barbituric acid itself or with such substitution products of the barbituric acid which contain one or more of the required substituents. In this case the substituents still missing are introduced into the barbituric acid or into its substitution products in the manner known per se. Instead of the barbituric acid itself or instead of its simple substitution products derivatives thereof may be used as starting materials in which case the intermediate products primarily formed are converted into the N-mono- or dialkylated C-methyl-C-alkyl-barbituric acid of the kind above specified in the usual manner. Thus, for instance, the N-monoalkylated compounds are advantageously obtained by the alkylation of cyano-imino derivatives of the barbituric acid, its C-substitution products respectively. The N-alkyl-N'cyano-imino barbituric acids containing at the 5-carbon atom a methyl group and an alkyl group of at least 3 carbon atoms as above specified which are obtained in this case as intermediate products are saponified to

the corresponding N-monoalkylated C-methyl-C-alkyl barbituric acids in the usual manner.

The salts of the new N-monoalkylated barbituric acid derivatives are obtained by neutralization with bases, for instance, calcium hydroxide, alkali metal hydroxide and amines, such as diethylaminoethanol and piperazine in the known manner.

The invention is further illustrated by the following examples without being restricted thereto:—

Example 1.—20 parts by weight of sodium are dissolved in 400 parts by weight of ethylalcohol and 50 parts by weight of methylurea, and 90 parts by weight of butylmethylmalonic acid ethylester are added. The mixture is heated for 8 hours to boiling. Then it is acidified with acetic acid and the alcohol is evaporated. Water is added to the residue, the reaction product is taken up in ether and the solution first shaken with a sodium bicarbonate solution and then with a normal aqueous solution of caustic soda. On acidifying the caustic soda solution the N-methyl-C,C-methyl-butyl-barbituric acid is precipitated. On redissolving from cyclohexane it melts at 87° C. The acid may also be distilled in vacuo. It boils at 133–135° C. under 1 mm. pressure.

With sodium alcoolate it can be readily transformed into the sodium salt which is readily soluble in water.

When starting with ethylurea N-ethyl-C-methyl-C-butylbarbituric acid is obtained in the manner described above.

In an analogous manner the N-methyl-C,C-(n-hexyl)-methylbarbituric acid can be obtained. It distils under 1.5 mm. pressure at 183–185° C., and crystallizes on cooling.

The N-methyl-C-cyclohexylethyl - C - methylbarbituric acid is obtained in a similar manner, for instance, when starting with methylurea and cyclohexylethyl-methyl-cyanoacetic acid ester while using sodium ethylate as a condensing agent. In this case the imino-N-methyl-C-cyclohexylethyl-C-methylbarbituric acid first formed is subsequently boiled for about 6–8 hours with 20% aqueous sulfuric acid.

Example 2.—9.5 parts by weight of sodium are dissolved in 200 parts by weight of dry ethyl alcohol and mixed with 42 parts by weight of methyl-allylmalonic ester and 20 parts by weight of methylurea while stirring. The mixture is heated for 6 to 8 hours under reflux. After cooling the salt which crystallizes out is filtered off, dissolved in water and the free acid is precipitated with acetic acid. On recrystallizing from water the N-methyl-C,C-methyl-allyl-barbituric acid melts at 135° C.

In an analogous manner also the N-methyl-C,C-bromoallylmethylbarbituric acid can be obtained. It distils under 1.5 mm. pressure at 136–138° C.

From allyl urea and methyl-isoamyl-malonic acid ester in an analogous manner the N-allyl-C-methyl-C - isoamylbarbituric acid is obtained which boils at 150° C. under 1 mm. pressure and melts at 68–69° C.

Example 3.—46 parts by weight of sodium metal are dissolved in 500 parts by weight of methanol, 92 parts by weight of dicyandiamide and 256 parts by weight of cyclohexyl-methyl-malonic acid diethylester (boiling at 137–138° C. under 1 mm. pressure) are added and the mixture is heated for 10 hours under reflux to 70–80° C. The mixture is then cooled and 140 parts by weight of dimethylsulfate are added drop by drop while

stirring, care being taken that the temperature does not exceed 50° C. After the reaction temperature has gone down the methylalcohol is distilled off, the residue is treated with the 6-fold quantity of its weight of a 20% aqueous solution of sulfuric acid and boiled for 6 hours under reflux while stirring. After cooling the N-methyl-C,C-cyclohexyl - methylbarbituric acid separated is sucked off and redissolved from dilute alcohol. Thus colorless needles melting at 157° C., are obtained. The sodium salt forms a white product which is readily soluble in water.

When using allyl or crotylbromide instead of dimethylsulfate as the alkylating agent, N-allyl- and N-crotyl-C-methyl - C - cyclohexylbarbituric acid are obtained.

When starting with cyclopentyl-methylmalonic acid ester, N-methyl-C-cyclopentyl-C-methylbarbituric acid is obtained in the form of white crystals.

The N-methyl-C,C-beta-ethylhexyl-methylbarbituric acid forms an oily product.

We claim:

1. Barbituric acid derivatives of the formula: 25

wherein R_1 stands for a cyclohexyl group, alkyl stands for a radical selected from the group consisting of saturated and unsaturated alkyl groups and X stands for a substituent selected from the group consisting of hydrogen and alkali and alkaline earth metals, which compounds are whitish crystalline products, insoluble in water in the form of the free acid but soluble in the form of the alkali metal salts. 35

2. Barbituric acid derivatives of the formula: 40

wherein R_1 stands for a cyclohexyl group, X stands for a substituent selected from the group consisting of hydrogen and alkali and alkaline earth metals, which compounds are whitish crystalline products, insoluble in water in the form of the free acid but soluble in the form of the alkali metal salts. 50

3. Barbituric acid derivatives of the formula: 55

wherein R_1 stands for a cyclohexyl group, which compounds are whitish crystalline products, insoluble in water in the form of the free acid but soluble in the form of the alkali metal salts. 60

4. Barbituric acid derivatives of the formula: 65

wherein R_1 stands for a radical selected from the group consisting of cyclopentyl, cyclohexyl, and cyclohexylalkyl groups, alkyl stands for a radical selected from the group consisting of saturated and unsaturated alkyl groups and X stands for a 75

5 substituent selected from the group consisting of hydrogen, alkali and alkaline-earth metals, which compounds are whitish crystalline products, insoluble in water in the form of the free acid but soluble in the form of the alkali metal salts.

5. Barbituric acid derivatives of the formula:

10

wherein R_1 stands for a radical selected from the group consisting of cyclopentyl, cyclohexyl, and cyclohexylalkyl groups, and X stands for a substituent selected from the group consisting of hydrogen, alkali and alkaline-earth metals, 5 which compounds are whitish crystalline products, insoluble in water in the form of the free acid but soluble in the form of the alkali metal salts.
